[57] CLAIM

The ornamental design for a table, as shown and described.

DESCRIPTION

FIG. 1 is a perspective view of a table showing my new design:

FIG. 2 is a top plan view thereof;

FIG. 3 is a right side elevation view thereof; the left side,
front side and back side being a mirror image.

FIG. 4 is a bottom plan view thereof;

FIG. 5 is a perspective view of a table showing the second
embodiment of my new design:

FIG. 6 is a top plan view thereof;

FIG. 7 is a perspective view of a table showing the third
embodiment of my new design; and,

FIG. 8 is a top plan view thereof.
